INHALER

Charles M. McNeill, Norwalk, Calif.

Application July 2, 1951, Serial No. 234,707

5 Claims. (Cl. 128—173)

1

This invention relates to an inhaler for medicinal purposes.

The object of the invention is to provide an inhaler which is compact and can be easily carried in a person's pocket until needed, the inhaler being constructed so that a medicinal solution arranged in the inhaler will be atomized or nebulized by inspiratory breathing.

Another object of the invention is to provide an inhaler which contains a medicinal solution wherein, upon inspiratory breathing by the user, a portion of the medicine will be shaken loose from a vibratory ribbon or reed to be intermixed with the incoming air current and create a fine spray.

A further object of the invention is to provide an inhaler which is extremely simple and inexpensive to manufacture.

Other objects and advantages will be apparent during the course of the following description.

In the accompanying drawings forming a part of this application, and in which like numerals are used to designate like parts throughout the same:

Figure 1 is a longitudinal sectional view taken through the inhaler, constructed according to the present invention;

Figure 2 is a longitudinal sectional view taken through the cap;

Figure 3 is a sectional view taken on the line 3—3 of Figure 1;

Figure 4 is a sectional view taken on the line 4—4 of Figure 1;

Figure 5 is a sectional view taken on the line 5—5 of Figure 1;

Figure 6 is a sectional view taken on line 6—6 of Figure 1.

Referring in detail to the drawings, the numeral 10 designates the casing or housing which may be fabricated of any suitable material, such as plastic. The casing 10 is adapted to hold a quantity of medicinal solution S therein, Figure 1. Supported on the top of the casing 10 is a collar 11, the collar 11 being cut away, as at 12, to define an annular shoulder so that the collar 11 will be supported upon the casing 10.

The upper portion of the collar 11 is cut away, as at 14, and extending upwardly from the collar 11 is a sleeve 15. The sleeve 15 defines a nose piece which can be inserted into the user's nostrils when the medicinal solution S is to be drawn into the nose or lungs of the user. The upper end of the sleeve 15 is open, as at 16, so that the spray containing the volatilized medicine can pass from the inhaler.

2

The sleeve 15 is provided with a plurality of spaced slots or openings 17, Figures 1 and 4, and extending downwardly from the sleeve 15 is a body member 18. The body member 18 may be fabricated of any suitable material, such as metal, and the lower end of the body member 18 is shaped to define a shank 19. The shank 19 extends downwardly into the solution S, and the shank 19 is provided with a slot 20 for a purpose to be later described.

The intermediate portion of the body member 18 is indicated by the numeral 21, and the intermediate portion 21 is provided with a cylindrical bore 22. The upper end of the body member 18 is shaped to define a chamber 23, Figure 1, and the bore 22 communicates with the chamber 23. The body member 18 is further provided with slots or openings 24 which communicate with the bore 22 so that air traveling through the casing 10 can pass into the bore through the openings 24. A reed or ribbon 25 extends downwardly through slot 20, and the reed 25 is fabricated of a material which will absorb or draw up some of the solution S by capillary action. The reed 25 is also flexible, so that as air is drawn up through the bore 22, the ribbon or reed 25 will vibrate, whereby some of the medicine on the upper portion of the reed 25 will be shaken loose or vibrated loose to become intermixed with the moving air current so as to create a medicinal spray.

Arranged within the sleeve 15 above the body member 18 is a baffle 26. The baffle 26 is provided with a plurality of radially extending slots or openings 27, Figures 1 and 3, and the baffle 26 serves to prevent any large droplets or particles of medicine from being carried into the nostrils or lungs of the user. A cap 28, Figure 2, is adapted to be inserted or positioned over the sleeve 15 when the inhaler is not being used, so that the contents of the inhaler won't deteriorate or become contaminated.

From the foregoing it is apparent that an inhaler has been provided wherein the upper end of the sleeve 15 can be inserted into the nostrils of the user after the cap 28 is removed therefrom. Thus, upon inspiratory breathing, air will be drawn in through the openings 17 in the sleeve 15, and this air will follow the paths indicated by the arrows in Figure 1. Thus, the air will pass downwardly through the casing 10, and then enter the bore 22 through the openings 24. The flexible reed 25 adsorbs or retains a quantity of the medicinal solution S due to capillary action of the reed 25, and as the air is sucked up through the bore 22, the reed 25 will vibrate so that a

portion of the fluid material thereon will be shaken loose and intermixed with the moving air. Thus, a spray containing atomized medicinal solution will be created, and this spray will pass up through the chamber 23, thence through the openings 21, and finally out through the openings 16 in the upper end of the sleeve 15 and into the nostrils and lungs of the user. The baffle 26 will prevent any large drops of medicine from passing through the sleeve 15.

The wick or reed 25 has its lower end anchored in the slot 20 in the shank 19, Figure 1. The wick 25 soaks up the medicinal solution by capillary action, so that the medicinal solution will be atomized as the user breathes. Thus, a fine spray will be produced as a result of the negative pressure of breathing. The baffle 26 catches the heavier droplets of medicine so that only the smallest particles of mist will pass out of the inhaler.

From the foregoing it is apparent that a means has been provided for breaking up a fluid by the low pressure of breathing into fine enough particles to float with the air stream into the lung passage. Thus, a person can breathe hard enough to vibrate a ribbon or a reed, in several different arrangements as previously described and the vibrations of the reed or ribbon have the necessary force to break up the fluid. Further, whenever fluid drops on a vibrating reed or spring it will be atomized or nebulized. This structure has been utilized in a medicinal applicator and will work properly and be small and cheap enough to be sold as a dispenser or container of the medicine purchased.

I claim:

1. In an inhaler, a casing adapted to contain a quantity of medicinal solution therein, a collar supported on the top of said casing, an open-ended sleeve extending upwardly from said collar and defining a nose piece, there being a plurality of spaced openings in said sleeve for the passage therethrough of air, a body member extending downwardly from said sleeve into the solution, said body member comprising a lower shank provided with a slot, the intermediate portion of said body member being provided with a bore, there being openings in said body member communicating with said bore, the upper interior portion of said body member being shaped to define a chamber, and a flexible reed projecting into said slot and extending through said bore.

2. In an inhaler, a casing adapted to contain a quantity of medicinal solution therein, a collar supported on the top of said casing, an open-ended sleeve extending upwardly from said collar and defining a nose piece, there being a plurality of spaced openings in said sleeve for the passage therethrough of air, a body member extending downwardly from said sleeve into the solution, said body member comprising a lower shank provided with a slot, the intermediate portion of said body member being provided with a bore, the upper interior portion of said body member being shaped to define a chamber, and a flexible reed projecting into said slot and extending through said bore, said reed adapted to vibrate upon inspiratory breathing of the user to cause the medicinal solution thereon to become atomized and create a spray with the moving air.

3. In an inhaler, a casing adapted to contain a quantity of medicinal solution therein, a collar supported on the top of said casing, an open-

ended sleeve extending upwardly from said collar and defining a nose piece, there being a plurality of spaced openings in said sleeve for the passage therethrough of air, a body member extending downwardly from said sleeve into the solution, said body member comprising a lower shank provided with a slot, the intermediate portion of said body member being provided with a bore, there being openings in said body member communicating with said bore, the upper interior portion of said body member being shaped to define a chamber, and a flexible reed projecting into said slot and extending through said bore, said reed adapted to vibrate upon inspiratory breathing by the user to cause the medicinal solution thereon to become atomized to create a spray with the moving air, and a cap for closing the upper end of the sleeve when the inhaler is not being used.

4. In an inhaler, a casing adapted to contain a quantity of medicinal solution therein, a collar supported on the top of said casing, an open-ended sleeve extending upwardly from said collar and defining a nose piece, there being a plurality of spaced openings in said sleeve for the passage therethrough of air, a body member extending downwardly from said sleeve into the solution, said body member comprising a lower shank provided with a slot, the intermediate portion of said body member being provided with a bore, there being openings in said body member communicating with said bore, the upper interior portion of said body member being shaped to define a chamber, and a flexible reed projecting into said slot and extending through said bore, said reed adapted to vibrate upon inspiratory breathing by the user to cause the medicinal solution thereon to become atomized and create a spray with the moving air, a cap for closing the upper end of the sleeve when the inhaler is not being used, and a baffle arranged transversely in said sleeve above said body member and provided with a plurality of spaced openings.

5. In an inhaler, a casing adapted to contain a quantity of medicinal solution therein, an open-ended sleeve extending upwardly from said casing and defining a nose piece, there being a plurality of spaced openings at the base of said nose piece for the passage of air into the casing, a body member extending downwardly from said sleeve into the casing, said body member comprising a lower shank provided with a slot, the remaining portion of said body member being provided with a bore, there being air openings in the lower end of the remaining portion of said body member communicating with said bore and with the interior of the casing, and a ribbon projecting into said slot and extending through said bore, said ribbon dipping into the solution in the casing, and means for securing the ribbon in place.

CHARLES M. MCNEILL.
